UNITED STATES PATENT OFFICE.

JAMES G. BUIS, OF COATESVILLE, INDIANA.

VALVE-OPERATING MECHANISM FOR INTERNAL-COMBUSTION ENGINES.

1,165,841.

Specification of Letters Patent. Patented Dec. 28, 1915.

Application filed June 24, 1914. Serial No. 847,165.

To all whom it may concern:

Be it known that I, JAMES G. BUIS, citizen of the United States, residing at Coatesville, in the county of Hendricks and State of Indiana, have invented certain new and useful Improvements in Valve-Operating Mechanism for Internal-Combustion Engines, of which the following is a specification.

10 My invention is designed as an improvement over a structure previously conceived by me and described in an application for Letters Patent dated Oct. 19, 1912, bearing Serial #726,742.

15 As its primary object, the present invention aims to provide an improved reciprocable valve, so arranged relatively to the engine crank shaft as to be actuated thereby, said valve operating within an auxiliary cylinder, open to the main or working cylinder of the engine, the intake exhaust ports being alternately opened and closed by movement of said valve to provide for the proper cycle of operation incident to the 25 use of an internal combustion engine of the four cycle type.

The invention as a further object contemplates means, such in its nature as to be driven directly by the engine shaft, said 30 means reciprocating the valve, said valve in turn being so timed as to admit a fresh charge to the working cylinder at alternate strokes of the engine piston.

The above and additional objects are 35 accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or 45 corresponding parts throughout the several views, and in which:

Figure 1 is a top plan view of an internal combustion engine constructed in accordance with the present invention; Fig. 2 is a 50 section on the line 2—2 of Fig. 1; Fig. 3 is a fragmentary section of one of the auxiliary cylinders, the valve-operable therein being shown in a position whereby both the fuel and exhaust pipes are closed; Fig. 4 is a 55 view similar to Fig. 3, the valve being shown in a position whereby the exhaust pipe is

open to the working cylinder; Fig. 5 is a section on the line 5—5 of Fig. 1; Fig. 6 is an edge view of the cam; Fig. 7 is a vertical section of the valve casing or auxiliary cylinder, looking toward the fuel intake and exhaust pipes; Fig. 8 is an elevation of one of the valves; and Fig. 9 is a section on the line 9—9 of Fig. 8.

Before proceeding with the description of the drawings, I desire to call particular attention to the fact that while I have evolved and shown my invention as being employed in connection with the stationary engine of the twin cylinder type, the same may be 60 readily utilized, if desired, in connection with a portable engine of the single cylinder type.

Referring now to the drawings by numerals, 1 designates as an entirety the main 75 or working cylinder of the engine, said cylinder having directly associated therewith a piston 2, piston rod 3, crank shaft 4 and igniter 5, the detail construction or formation of which may be varied or modified as 80 desired, said elements in no way forming a feature of the present invention; they being illustrated only to convey the idea in mind.

Formed separately or integral, (as shown) 85 with the cylinder 1 is an auxiliary cylinder 6, said cylinder being provided with a water jacket 7 and removable cylinder-head 8, and having attached thereto, preferably in spaced relation as shown, an intake pipe 9 and exhaust pipe 10, said two pipes being 90 disposed respectively below and above the horizontal plane of a port 11 communicating the interior of cylinder 6 with the working cylinder 1, said port 11 being open to the latter cylinder at a point adjacent its upper 95 end.

Within cylinder 6 and extending parallel with crank shaft 4 is an auxiliary or valve operating shaft 12, said shaft having mounted thereupon a cam device designated as an 100 entirety by the numeral 13, the working surface of the said cam being so formed as to operate upon a bell crank 14 in a manner much the same as the cam device disclosed in my previous application acts upon the 105 bell crank shown therein. Pivoted to bell crank 14 as at 15 is a valve piston 16 the opposite end of which is pivoted as at 17 within an opening 18 in the base of a reciprocable cylindrical valve member 19 which, 110 in the absence of a better term will be hereinafter referred to as a "piston-valve". The

bore of the piston valve 19 is constricted at a point intermediate its ends as at 20, the exterior surface of the said constricted portion being annularly grooved as indicated at 21, said groove, forming, in one position of the valve, the intake passage way and in another position, the exhaust passage way of the engine. Packing rings 22 embrace the piston-valve as shown. Attached as at 10 23 to the cylinder head 8 is a helical spring 24, the opposite end of the spring being attached as at 25 to the end of valve rod 16, said spring serving as a cushion whereby the sudden movement incident to the valve, 15 when in use, is to a certain extent rendered less apparent. Any suitable means such as a chain 26 operating over sprockets 27 and 28 may be utilized to transmit motion to the shaft 12 from the crank shaft 4, said 20 sprockets however, being such in size, as to rotate shaft 12 but once, while crank shaft 4 is making two complete revolutions.

The cycle of operation is as follows: When the parts are in the position shown in Fig. 2, 25 the piston is moving downwardly and taking the charge from the fuel pipe around the annular groove in valve 19. At that time lever 14, see Fig. 5, is traveling along the left-hand bend of the flange on cam 13. 30 By the time the charging stroke of the piston is ended, the lever 14 will reach the straight portion of the cam flange. That brings the valve in the position shown in Fig. 3 where everything is closed. The lever continues 35 to travel on the straight portion of the cam flange during both the compression stroke and the explosion or power stroke of the piston and, therefore, during those two cycles, the valve closes the fuel and exhaust 40 pipes, as shown in Fig. 3. On the exhaust stroke, the lever 14 travels along the right-hand bend B, shown in Fig. 5, and that moves the valve up to its highest position, as shown in Fig. 4, so as to uncover the 45 exhaust pipe, thus permitting the burnt or exhaust gases to escape.

From the foregoing, taken in connection with the accompanying drawings it is apparent that the operation of piston valve 19 50 is so timed as to move annular groove or passage way 21 into registration with intake pipe 9 and exhaust pipe 10 at each alternate stroke of working piston 2; that the spring 24 acts only as a cushion to relieve the piston 55 19 of the shock or jolt that would otherwise be apparent by reason of its sudden movement; and that by the use of the valve mechanism above described, a single port, namely 11, is utilized to admit and exhaust both the

fresh and spent gases incident to the use 60 of the engine.

In reduction to practice, I have found that the form of my invention, illustrated in the drawings and referred to in the above description, as the preferred embodiment, is 65 the most efficient and practical; yet realizing that the conditions concurrent with the adoption of my device will necessarily vary, I desire to emphasize the fact that various minor changes in details of construction, 70 proportion and arrangement of parts may be resorted to, when required, without sacrificing any of the advantages of my invention, as defined in the appended claims.

Having thus fully described my invention, 75 what I claim is new and desire to secure by Letters Patent, is:—

1. The combination with an explosive engine, of valve mechanism therefor including an auxiliary cylinder mounted at one 80 side of the engine cylinder with its axis parallel to the axis of said engine cylinder, a piston like valve operating within said auxiliary cylinder, a spring attached at one end to said piston valve and at its opposite 85 end to the cylinder top to cushion movement of the valve, a valve operating shaft, a cam device mounted on said shaft and provided with an irregular peripheral flange, a lever of the bell crank type mounted in the crank 90 case of the engine, said lever being provided with a bifurcated terminal arranged to straddle the flange aforesaid, a connection between the bell crank and the valve like piston to control movement of said valve, 95 and a means to rotate said valve operating shaft.

2. The combination with an explosive engine, of valve mechanism therefor including an auxiliary cylinder mounted at one 100 side of the engine cylinder with its axis parallel to the axis of said engine cylinder, a piston like valve operating within said auxiliary cylinder to control the intake and the exhaust of the engine, and a single helical spring affixed at one end to the cylinder top and at its opposite end to the valve piston to cushion the movement of said piston and to assist directly in its operation for the purpose specified, and a means to control movement of said valve.

In testimony whereof I affix my own signature in presence of two witnesses.

JAMES G. BUIS.
